The ornamental design for a building base for a toy vehicle, as shown and described.

DESCRIPTION

FIG. 1 is a top perspective view of the building base for a toy vehicle showing my new design;

FIG. 2 is a front elevational view thereof;

FIG. 3 is a side elevational view thereof, the other side being identical;

FIG. 4 is a rear elevational view thereof;

FIG. 5 is a top plan view thereof; and,

FIG. 6 is a bottom plan view thereof.

FIG. 1

FIG. 4

FIG. 2

FIG. 3

FIG. 5

FIG. 6
